RESETTER FOR WEFT REPLENISHING LOOMS

Richard G. Turner, Worcester, Mass., assignor to
Crompton & Knowles Loom Works, Worcester,
Mass., a corporation of Massachusetts

Application August 18, 1938, Serial No. 225,607

3 Claims. (Cl. 139—231)

This invention relates to improvements in weft replenishing looms and it is the general object to provide improved mechanism for resetting the weft replenishing mechanism incident to an operation thereof.

In the usual bobbin changing multicolor loom the weft detector is located at the magazine side of the loom and upon indication of substantial weft exhaustion in the active shuttle effects a lifting of a vertical slide or the like which stores the indication for future use. If the depleted shuttle remains active the slide is lowered to set the magazine for transfer within two beats of the loom. This setting or initiation of transfer includes the lifting of a transfer latch into the path of a lay carried bunter and the placing of a shuttle feeler in shuttle detecting position. After transfer is initiated, therefore, the slide is back in normal position and cannot again call a transfer unless lifted by the feeler. Should the shuttle fail to be completely boxed on a transferring beat of the loom it will move the shuttle feeler and simultaneously take the latch out of the path of the lay bunter to revoke the transfer. Since the slide is now restored to normal position, that particular replenishing cycle is lost, and an entirely new cycle must be started by another indication by the weft detector.

At least two picks of the loom intervene between indication by the weft detector and transfer due to the fact that the detector is on the magazine side of the loom. If the misplaced shuttle is so far out of the box that the detector cannot give an indication of exhaustion, the empty shuttle will leave the magazine side of the loom on what was intended to be a transferring beat without having initiated another replenishing cycle. After another two picks the shuttle will be back under the magazine and if properly placed can initiate a second replenishing cycle, but it will be an additional two picks before replenishment can take place. From this it will be seen that when replenishment is revoked there is a probability that four additional picks of the shuttle will occur before it is replenished. If the weft detector is properly set to leave a minimum of waste yarn on the bobbin there will not be enough weft for these additional four picks without likelihood of stopping the loom through the filling stop motion.

It is an important object of my present invention to provide replenishing mechanism so constructed that once the indication of weft exhaustion is given by the detector the transerrer mechanism will make repeated efforts to effect transfer subsequent to revocation by the shuttle feeler without the necessity of a second indication by the weft detector. This result I may effect by employing a type of controller corresponding to the aforesaid vertical slide but arranged to re-

main in position to call or initiate transfer until reset by the transfer mechanism.

It is a further object of my present invention to provide a train of mechanism to effect transfer wherein there is located between the weft detector and the transfer mechanism a form of control for the transerrer which remains in set position after the transerrer latch has been set for transfer. My present invention differs markedly in this respect from previous weft replenishing mechanisms where the controller has been reset in the act of placing the latch for transfer. Because of the fact that the controller remains in indicating position I am able to call another transfer should the first one be revoked and it is this characteristic of the controller which makes an intervening indication by the weft detector unnecessary.

In my co-pending application Serial No. 190,-637 I have shown a pneumatic thread extractor to remove the thread extending from the selvage to the shuttle under the magazine and including positioning means operated by the transerrer arm to move the extractor from its normal inoperative position to thread extracting position. The extractor operates on transferring beats only of the loom and therefore becomes a part of the transferring cycle. It is a further object of my present invention to provide means for initiating repeated transfer cycles including the operation of the extractor from a single indication of the weft detector. As a further feature of this part of my invention I derive the force for resetting the aforesaid controller from some part of the extractor, since both the extractor and the resetter operate in timed relation with the transfer mechanism and are dependent upon the latter and it is convenient because of the location of the extractor to use a connection from it to the resetter.

With these and other objects in view which will appear as the description proceeds, my invention resides in the combination and arrangement of parts hereinafter described and set forth.

In the accompanying drawings, wherein a convenient embodiment of my invention is set forth, Fig. 1 shows a loom with a lay on front center in which position the weft detector can initiate a replenishing cycle and wherein the preferred form of my invention is shown in the normal or non-operating position.

Fig. 2 is a view similar to Fig. 1 but with the replenishing mechanism shown in full lines as set for a transfer and showing in dotted lines the controller being reset at the time of transfer.

Fig. 3 is a plan view taken in the direction of arrow 3, Fig. 1 of the shuttle and weft detector with adjacent parts shown on an enlarged scale and with the shuttle shown misplaced widely enough to prevent operation by the weft detector,

Fig. 4 is a detailed vertical section on line 4—4 of Fig. 3.

Fig. 5 is an enlarged vertical section on line 5—5 of Fig. 1.

5 Fig. 6 is a diagrammatic view showing the type of loom by means of which my invention is illustrated in the present instance.

10 Fig. 7 is a side elevation of parts of a loom showing a modified form of my invention combined with a thread extractor and shown as though viewed from the left of Fig. 3.

Fig. 8 is a top plan view of the structure shown in Fig. 7, and

15 Fig. 9 is an enlarged elevation taken in the direction of arrow 9, Fig. 8.

20 In the description to follow I have illustrated my invention in connection with weft replenishing mechanisms shown in certain of my copending applications but I do not wish to have my invention limited to use with such inventions. The reserve bobbin magazine to be described is of the rocking type, but the invention forming the subject matter of this application is not restricted to this type of bobbin magazine. I also show recently developed means for setting and revoking the magazine for transfer and have employed a type of color control for the magazine similar to that already extensively used on shuttle changing looms, but my present invention is not confined in its utility to use with these particular mechanisms.

25 Referring to Figs. 1 and 2, the magazine M rocks about a fixed pivot 10 and has front and rear bobbin chutes 11 and 12, respectively. The magazine is normally in the position shown in Fig. 1 with the lowest bobbin of the front stack under a transerrer arm 13 pivoted on a fixed stud 14. The magazine retains this position during shifting of the shuttle boxes G at the opposite 30 end of the loom shown in Fig. 6 until replenishment is called, whereupon its position will be determined by the active shuttle. As shown herein there will be two weaving shuttles S' and S2 either one of which may be active for as long 35 a period as desired and under control of any one of the well-known box pattern mechanisms not shown. If shuttle S2 corresponding to the weft in the front stack is to be replenished, the magazine will remain as shown in Fig. 1, but if shuttle S' corresponding to the bobbins in the rear stack 40 is empty, the magazine will be rocked to place the lowest shuttle of the rear stack under the transerrer arm as shown in Fig. 2.

45 The mechanism for rocking the magazine includes a rod 15 pivoted to the upper part of the magazine and attached to lever mechanism 16 moving about a fixed pivot 17 and actuated by a depending rod 18 provided with a hook 19. The hook passes through and has its position determined by an oscillatable lever 20 pivoted at 21 on a fixed bracket 22 secured to a stationary stud 23 carried by the loomside. The lower arm 24 of lever 20 is attached to a flexible connector 25 which extends around a sheave 26 mounted on the bracket 22 and leads to the opposite side of the loom where it extends up around a second sheave 27, see Fig. 6, to a connection 28 with the box mechanism G. The rising and falling motions of the shifting shuttle boxes at the left hand side of the loom are therefore communicated to the lever 20 and when the bottom box 29 is raised to picking position opposite the shuttle race R, connection 25 will be pulled to swing lever 20 to the right as viewed in Fig. 1 and thereby move

the hook 19 out of the path of an operating stud 30.

If, on the other hand, the upper box 31 is active spring 32 will act to hold lever 20 in its normal left hand position to place hook 19 under the stud 30. Under these conditions downward motion of said stud 30 will depress the hook and cause rocking of the magazine in a right hand direction as viewed in Fig. 1 to place the bottom bobbin of the rear stack under the transerrer 10 arm. Certain features of the magazine not directly concerned with the present invention have been omitted and reference may be had to copending application Serial No. 129,245 for further details of the construction and operation of 15 the magazine.

The aforesaid stud 30 is mounted on a normally stationary lever 35 pivoted loosely on the stud 23 and normally held in its down position partly by gravity and partly by spring 36. The forward end of the lever, at the left of Fig. 1, carries a lifting stud 37 attached to a yieldable rod head 38 having front and back members 39 and 40, respectively, held together by a spring 41. These elements 39 and 40 are normally connected 25 to the stud 37 as shown in Fig. 1 so that up motion of the forward end of lever 35 will cause rising of the head 38 and a corresponding up motion of setting rod 42.

The upper end of rod 42 is connected as at 45 30 to a setting lever 46 pivoted as at 47 to a fixed adjustable bracket 48. The lever 46 carries a latch lifting finger 50 disposed under the transfer latch 51 pivotally connected as at 52 to the transerrer arm 13. The upper end of the setting lever 46 carries a shuttle feeler 53 by means of which transfer may be revoked by a misplaced shuttle.

The mechanism for resetting lever 46 and parts moving therewith may be the same as set forth 40 in my co-pending application Serial No. 192,783. The resetting is accomplished briefly as follows:

45 When the initiated transfer is revoked by engagement of a misplaced shuttle with the shuttle feeler, the lever 46 is moved from the full to the dotted line position shown in Fig. 2, thereby depressing rod 42 and moving the transfer latch out of the path of the lay bunter to prevent transfer. Before another transfer can be initiated it is necessary to reestablish connections between 50 rod 42 and lever 35. With the particular type of magazine shown it is necessary that the cam 57 exercise its control throughout the transferring interval so that the magazine cannot start a rocking motion while the transerrer arm is down. The 55 cam shown in Fig. 2 accomplishes this result by means of dwell 58. The stud 37 is therefore in raised position during revocation of transfer and the rod head 38 assumes the position shown in dotted lines in Fig. 2. After the necessity for 60 maintaining the magazine in proper position has passed the left end of lever 35 is lowered by cam action and the stud 37 moves down relatively to the head to reestablish driving connection between said stud and the head 38. A stop screw 65 59 arrests motion of lever 46 before stud 37 has reached its lowest position, thereby permitting reestablishment of the connection by continued down motion of the stud 37. In this way the parts which initiate a transfer are reestablished or reset 70 subsequent to a revocation so that when the point is reached in the next loom cycle for initiating transfer the rod 42 can again be raised.

In order that lever 35 may be rocked to shift the magazine if necessary and set lever 46 for 75

transfer I provide a regularly moving actuator lever 55 pivoted on the stud 23 which carries an operating roll 56 driven by a grooved cam 57 which acts to lift the forward end of lever 55 once every two picks of the loom and at a time which will set the magazine for transfer prior to the arrival of lay L in its foremost position on a transferring beat of the loom.

The controlling connection between levers 35 and 55 includes a lifting dog 60 having a shoulder 61 and pivoted to lever 55 and normally rising in a plane to one side of a lifting lug 62 on the lever 35. The regular actuation of lever 55 therefore has no effect on lever 35 on non-transferring cycles of the loom, but when a transfer is called or initiated dog 60 is moved to the left as viewed in Fig. 5 so that it will be under the lug 62 and lift the lever 35 during rising motion of the forward end of lever 55.

The controlling mechanism for the dog 60 includes a pair of controllers or fingers 65 and 66 each having a head 63 pivoted to a rod 67 carried by a sliding frame 68 mounted on guide rods 69 supported by the lever 35. Each member 65 and 66 is connected to a yielding locking plunger 70 surrounded by a spring 71 and passing through a part of the frame 68 as shown in Fig. 5. The effect of the rocking plunger and its spring is to hold the members 65 and 66 in either of their extreme angular positions. Normally the controllers will be in the position of member 66 as shown in Fig. 5.

Each controller carries a lifting latch 73 which can be positioned over a lifting finger 74 on a setter 75 movable pivotally about rod 76. The member 75 is connected by a link 77 to the core 78 of a solenoid 79 supported by the lever 35.

The solenoid is controlled by a weft detector designated generally at D, Figs. 1 and 3, having two pins 80 and 81 normally insulated from each other but adapted to be connected electrically by a ferrule 82 on the bobbin 83 in the shuttle to be replenished. The pins 80 and 81 are connected, respectively, to wires 84 and 85 one of which leads to a source of power 86 and the other of which leads to the solenoid 79. A wire 87 connects the other side of the source of power to the other side of the solenoid. So long as the detector pins engage a sufficient supply of weft in the shuttle they will be insulated from each other and the solenoid will remain unenergized, but at substantial exhaustion of weft the ferrule will be uncovered to connect the detector fingers, whereupon current will flow in the circuit indicated in Fig. 2 to energize the solenoid 79 the effect of which is to lift the link 77 and elevate the setting finger 74.

The setting finger 74 can operate but one of the latches 73 at a time because of a control exercised over the latches 73 and the controllers 65 and 66 to which they are connected by means of the lever 29. The latter is connected by a rod 88 to the sliding frame 68 to move the latter and place one or the other of the latches 73 over the finger 74. As shown in Fig. 2 the rear latch 65 is in alignment with finger 74 and corresponds to the rear stack of reserve bobbins in the magazine and the shuttle S' in the top shifting shuttle box 31.

The lower end of each of the controllers 65 and 66 is adapted for cooperation of a shoulder 61 on the dog 60, the shoulder being narrow enough to be engaged by one only of the controllers 65 or 66 at a time, and by the member which has been moved to the indicating or con-

trolling position illustrated for member 65 in Fig. 5. During rising motion of the dog its shoulder engages the controller which is in indicating position and aligned with it, such as 65 in Fig. 5, and upon further upward motion the dog is moved to the left under the lug 62 of lever 35. The latter is thereby raised to set the lever 46 in transfer position with the latch 51 in the path of bunter 49 and the shuttle feeler in shuttle detecting position shown in full lines, Fig. 2. The controller which is in non-indicating position, at 66 in Fig. 5, has no effect on the dog 60 and likewise should the frame 68 be shifted so that the controller 65 in indicating position is out of alignment with the shoulder 61, the dog will rise without being directed toward the lifting lug 62. The only time that the dog is shifted to the position shown in Fig. 5 is when one or another of the members has been moved to indicating position and is in alignment with shoulder 92. For a further understanding of the mechanism set forth in Fig. 5 reference may be had to Patents Nos. 2,054,174 and 2,054,192.

In the operation of the mechanism thus far described the boxes G will shift vertically to render one or the other of the boxes 29 or 31 active so that the shuttle carried thereby will be picked to the right hand or magazine side of the loom as viewed in Fig. 6. With each shift of the boxes there will be a rocking of lever 20 and a longitudinal sliding motion of frame 68 with respect to the lever 35 and there will also be a change in the relation between hook 19 and stud 30, all of these changes being effective through the flexible connection 25. So long as the weft in the active or running shuttle is sufficient for continued weaving it will engage the detector pins 80 and 81 without connecting the latter electrically and the solenoid will remain unenergized. When an exhausted shuttle is presented to the detector mechanism, however, the pins will be connected electrically and the previously described results accomplished through the energization of the solenoid. Thereafter rising motion of dog 60 will cause rocking of the setting lever 46 to move the latch 51 and the shuttle feeler 53 to transfer positions to initiate transfer, and if necessary there will also be a rocking of the magazine.

The mechanism thus far described and its operation may be as set forth in the aforesaid co-pending applications and patents. It is to be understood that forward motion of the lay will cause engagement of its bunter with the latch 51 to depress the transerrer lever 46 from the full to the dotted line position shown in Fig. 2. It will be obvious that some provision must be made for resetting the controllers 65 and 66 after they cause a transfer and my present invention relates more particularly to means for effecting this resetting.

In carrying my invention into effect I pivot a lever 90 to the loom frame as at 91 and extend the same forwardly to support a roll 92 for engagement with an inclined plate 93 carried by an arm 94 pivoted to the transfer stud 14. In order to connect the transerrer arm and the arm 94 I provide a bolt 95 which extends through a spacing collar 96 engaging adjacent surfaces of the transerrer arm and the arm 94, see Fig. 4. Nuts 97 may be used to tighten the arms 13 and 94 against the collar 96, thereby causing these parts to move together as a unit.

It will be seen from the description already given that down motion of the transerrer arm 75

will lower the plate 93 with corresponding descent of lever 90 against the action of a spring 98 which normally holds the lever raised.

A two-part rod 100 is connected to the lever 90 as at 101 and is adjustable as to length by means of turn-buckle 102. The lower part of the rod passes through a guide 103 mounted on the loom-side. A stop collar 104 having its longitudinal position along the rod determined by a set screw 105 engages stop 103 to limit upward motion of the rod 100 and lever 90. The normal position of the lever 90 is up as shown in full line position of Figs. 1 and 2 so that the lower end of rod 100 is above the controllers 65 and 66 and their latches 73.

When a transfer occurs stud 95 will cause lowering of plate 93 and roll 92 to push rod 100 down against head 63 of the indicating finger which has been set for controlling relationship with the dog 60. The rod 100 moves in a line to one side of the pivot 67 for the controllers and therefore exerts a force tending to move the controller it engages in a left hand direction as viewed in Fig. 5. In that figure descent of the rod 100 will cause the latter to engage the head 63 of controller 65 and as the rod moves to the dotted line position shown in Fig. 5 controller 65 will be swung in a counter-clockwise direction to the position illustrated for controller 66. The spring plunger 70 will thereafter serve to hold the reset controller out of the path of the shoulder 61. It will be understood of course that either of the controllers 65 or 66 will remain in indicating position so long as rod 100 is in its normally raised position.

The advantage of the invention just described over those heretofore employed will be understood by reference to Fig. 3, where it is assumed that the magazine has been set for transfer as already described but the shuttle has failed to be properly boxed, and is misplaced so widely that the detector fingers 80 and 81 cannot enter slot 106 in the front wall of the shuttle. Under these conditions the detector cannot give an indication of weft exhaustion and forward motion of the shuttle feeler by the shuttle will rock the setting lever 46 in a left hand direction as viewed in Fig. 2 from the full to the dotted line position, thereby lowering the transfrerer latch 51 out of the path of the bunter on the lay to prevent transfer.

The transfrerer will be maintained raised in its normal position by the usual spring 107 and rod 100 will not be depressed. The controller which had directed dog 60 under lug 62 will remain in indicating position and on the next up motion of the forward end of lever 55 in the following transfer cycle rod 42 will again be raised to set the magazine for transfer despite the fact that the weft detector has not been able in the meantime to give a second indication of weft exhaustion. This last named feature represents an important departure of my present invention over prior practice. As heretofore made multi-color bobbin changing looms reset the magazine whenever a revocation occurs, requiring the detector to give another indication two picks after the position shown in Fig. 3 before another transfer cycle can be started, after which two additional picks will be necessary because of the fact that the detector is on the magazine side of the loom. Prior mechanisms require four picks of the shuttle subsequent to the condition shown in Fig. 3 before transfer can occur, but in my present invention only two picks are needed and the danger of the bunch becoming exhausted to ef-

fect loom stoppage through the filling stop motion is greatly reduced.

As previously stated I may combine the aforesaid resetter for the controller with a pneumatic thread extractor of the type set forth for instance in my co-pending application Serial No. 190,637 and as shown in Figs. 7 and 8. In this modification shown in those figures I retain the general feature of resetting the controller by some part which moves on a transferring beat of the loom but include in the transferring cycle a thread extractor which will ordinarily operate somewhat later in the cycle than the transferring mechanism but which should not operate unless there has already been a transfer.

In carrying this modification of my invention into effect I provide a fixed stand 110 carrying a stud 111 on which is mounted a fixed disk 112 and a movable disk 113 between which is located a friction disk 114. A nut 115 clamps the disks 112 and 113 together to constitute a frictional support for a rod 116 which moves with the movable disk. This rod carries at its forward end a head 117 through which vertically extends a hollow thread extractor tube 118 the lower end of which is provided with a thread notch 119 to be located normally behind the weft W extending from the selvage to the shuttle under the magazine. The notch leads to a mouth 120 into which the thread is drawn when a vacuum is set up in the tube 118 by a pump 121. The latter is operated by a connection 122 from the lay L to cause a partial vacuum in flexible tube 123 connected to tube 118 during backward motion of the lay subsequent to transfer. A thread accumulator 124 may be interposed in the tube 123 if desired.

The head 117 supports a roll 130 to be engaged by a shelf 131 on the transfer arm 126 when the latter descends to move the rod 116 and tube 118 around the stud 111 as a center. It is to be understood that the rod 116 is normally raised so that the end of tube 118 clears the lay, but upon transfer the shelf 131 depresses the head and forward end of the rod to lower the mouth 120 from its normally raised non-extracting position to the down extracting position. This part of the mechanism shown in Figs. 7 and 8 may be as set forth in the aforesaid co-pending application Serial No. 190,637 to which reference may be had for further details of construction and operation.

In utilizing the thread extractor to operate my present resetter I provide a lever 140 moving about a fixed pivot 141 and having a roll 142 to enter the forked end of an arm 143 moving with and supported by the movable disk. A second arm 150 fixed to the pivot 141 is attached to a depending rod 151 which corresponds to rod 100. This rod 151 may be adjusted and guided as is rod 100. The movable disk has an upwardly extending arm 145 on which is mounted an adjustable screw 155 which engages the lay when the latter moves rearwardly after downward motion of the extractor. The motion derived by the screw from the lay is sufficient to elevate the extractor to its normally inoperative or non-extracting raised position.

In operation, the extractor will normally be raised with the levers 140 and 150 in their full line positions shown in Fig. 9. When a transfer occurs the transfrerer arm 126 descends in a manner similar to the operation of transfrerer arm 13 to effect motion of the extractor from raised to lowered position. During descent of the extractor the pin 142 will move in a counter-

clockwise direction around stud 141 as viewed in Fig. 7 to move lever 140 to the dotted line position of that figure, whereupon force will be transmitted to rock the shaft 141 and lever 150 in a counter-clockwise direction and depress rod 151. Down motion of the last named rod will be accompanied by the same result as that already described in connection with Fig. 1, the resetting force, however, being derived from motion of the extractor. On the following backward motion of the lay the latter will engage the setting screw 155 and the parts will be returned from the dotted to the full line position of Fig. 9 to effect resetting of the thread extractor in its normally raised position and to lift the resetter for the controller.

In the modification the resetting of the controller occurs at the same time as in the preferred form, but return of the resetting rod to its normally raised position occurs somewhat later and when the lay is on back center. This delay is of no consequence inasmuch as the rod 151 is raised before the controller can again be positioned by the solenoid. It will also be understood that the control exercised through the pneumatic extractor may be in conjunction with a shifting shuttle box weft replenishing loom, but it is to be noted that the setting of the controller, the initiation of transfer, the completion of transfer, or revocation thereof, and ultimate resetting of the controller can all take place while a single shuttle is active and for this reason certain features of my invention are not essentially restricted to a multicolor loom.

From the foregoing it will be seen that I have provided simple means for resetting the indicating parts of weft replenishing mechanism to normal position by a connection from the transerrer arm. While I have shown a particular means for returning the controllers 65 and 66 to normal position actuated by the transerrer arm, yet I do not wish to be limited to this construction inasmuch as it is sufficient if the condition which effects resetting of these controllers is made dependent upon operation of the transerrer arm. It will further be seen that my present invention acts in such a way that a single indication of weft exhaustion by the detector will maintain the automatic features in condition to call for transfer repeatedly without requiring an intervening or repeated indication by the weft detector. This last feature greatly reduces the likelihood that the loom will stop due to complete exhaustion of the weft on those beats of the loom when transfer is revoked by a shuttle so widely displaced that the weft detector cannot give a second indication. It will further be seen in the modification that I have also combined the transfer mechanism and the resetter for the controller with a pneumatic thread extractor, the latter supplying the requisite force to operate the resetter for the controller and by its nature being closely associated with the transfer mechanism and forming a part of the replenishing cycle of the loom.

Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism having a reserve bobbin to be inserted into the shuttle, transfer mechanism to insert the reserve bobbin

substantial exhaustion of weft in the shuttle, a controller for the transfer mechanism, means actuated by the weft detector to move the controller from idle to working position when the weft detector indicates exhaustion of weft in the shuttle, retaining means to hold the controller in working position, means controlled by the controller when the latter is in working position to cause the transfer mechanism at a given point in each cycle of the loom subsequent to movement of the controller to working position to attempt to insert the bobbin into the shuttle, preventer means controlled by a misplaced shuttle to prevent operation of the transfer means, said retaining means holding the controller in working position subsequent to action of the preventer means and thereby enabling the controller to cause the transfer means to make another attempt to transfer the bobbin, and means operated by the transfer mechanism to return the controller to idle position upon operation of the transfer mechanism.

2. In a weft replenishing loom having a reserve bobbin to be inserted into a shuttle, transfer mechanism effective upon a complete operation thereof to insert the bobbin into the shuttle, a controller for the transfer mechanism movable from normal to indicating position upon occurrence of weft exhaustion in the shuttle, means controlled by the controller when the latter is in indicating position to initiate an operation of the transfer mechanism at regularly recurring intervals, means to complete the operation of the transfer mechanism if the shuttle is properly boxed, revoking means to prevent complete operation of the transfer mechanism if the shuttle is misplaced, means to hold the controller in indicating position subsequent to an operation of the revoking means, whereby the controller when in indicating position will repeatedly initiate an operation of the transfer mechanism at said regularly recurring intervals until said means to complete the operation of the transfer mechanism gives the latter a complete operation, and means operated by the transfer mechanism to move the controller from indicating to normal position only when the transfer mechanism has a complete operation.

3. In a weft replenishing loom having a reserve bobbin to be inserted into a shuttle by transerrer mechanism; a weft detector, a controller normally in idle position, means controlled by the detector to move the controller to working position when the detector indicates weft exhaustion, a shuttle position feeler normally in non-feeling position, operating means for the transfer mechanism normally in non-operating position, an actuator controlled by the controller and having regularly recurring actuating strokes, setting means to be connected to the actuator by the controller when the latter is in working position on each actuating stroke of the actuator to move the shuttle position feeler to shuttle feeling position and place the operating means in position to operate the transfer mechanism, a misplaced shuttle moving the shuttle position feeler from shuttle feeling to non-feeling position and moving the operating means for the transfer mechanism to non-operating position, means operated by the transfer mechanism when the latter has a transferring operation to return the controller to idle position, and means to maintain the controller in working position independently of motion of the shuttle position feeler.
